JOHN H. TROWBRIDGE, OF NEW HAVEN, CONNECTICUT.

Letters Patent No. 99,372, dated February 1, 1870.

MACHINE FOR PACKING TOBACCO.

The Schedule referred to in these Letters Patent and making part of the same.

I, JOHN H. TROWBRIDGE, of the city and county of New Haven, and State of Connecticut, have invented certain Improvements in Machines for Automatically Packing Fine-Cut Tobacco into metal foil or paper wrappers, of which the following is a specification.

Nature and Objects of the Invention.

The object of my invention is to provide a method of packing fine-cut tobacco, either smoking or chewing, into metal foil or paper wrappers without the aid of manual labor.

The tobacco being fed, the quantity to be packed separated and measured, and the entire operation of packing performed and completed by automatic machinery. The metal foil or paper for the wrappers is also supplied to the folding-device in a similar manner.

The entire machine is constructed and arranged in a compact and simple form, and the packages produced are regular and exact in shape, as well as even in quantity and weight.

In the drawings, which form a part of this specification—

Figure 1 is a plan or top view of a machine embodying my invention.

Figure 2, a front elevation of the same.

Figure 3, a side elevation of the carrying-trough and device for separating and measuring the tobacco.

Figure 4, a side elevation of the folding-device, showing the operation of the knives.

Figure 5, a side elevation of the device for supplying and feeding the wrappers to the folding-device.

Figure 6, a sectional view of the self-feeding hopper, taken on the line $z-z$ in fig. 2.

Figure 7 is a modification of the device shown in fig. 5.

A is the frame or bed of the machine.

B is the main shaft, from which motion is communicated to the various operating parts. The pulley for driving the same may be located at either end of the shaft, as may be most convenient.

C is the hopper, into which the tobacco to be packed is deposited.

This hopper contains a feeding-device for conveying the tobacco in regular and even quantities into the carrying-trough E.

This feeding-device consists of a revolving drum, a, carrying a series of combs or fingers, b. These combs or fingers have a reciprocating motion imparted to them at certain periods during each revolution of the drum a, by means of the eccentric cams a^1 and a^2 in the sides of the hopper-frame.

These combs or fingers are, by the action of the cams a^1 a^2 , forced out of the drum as it revolves through the hopper, entering the tobacco and carrying

it, as the drum revolves, through the lower end of the hopper into the carrying-trough E. The combs or fingers are at this point retracted into the drum, leaving the tobacco free to be carried forward in and by the carrying-trough E.

Motion is imparted to the drum a from the cam D^1 on the main shaft, which actuates the rack d^2 and cog d^3 through the lever d^1 , causing the drum to revolve such distance as may be necessary to supply the carrying-trough with the quantity of tobacco desired. During the reverse motion of the rack d^2 and cog d^3 , the drum is held at rest by means of a pawl and ratchet.

The carrying-trough E is composed of the flange-box or guide E^1 , and the three endless belts or bands e^1 , e^2 , and e^3 . These endless belts operate on the interior of the box E^1 , (it being open at the top,) passing around the pulleys e^1 e^2 e^3 e^4 e^5 and e^6 .

These pulleys are geared together, as seen at e^6 in fig. 3, and motion is imparted to them from cam D^5 on the main shaft, the cam actuating the lever d^4 , and, by means of the rack d^5 and cog d^6 , causes the endless belts forming the carrying-trough to move forward at the same time, and at each revolution of the main shaft, the length of a package of tobacco, or such distance as may be desired.

This carrying-trough and the feeding-hopper operate in unison with each other; that is, the drum a in the hopper feeds the tobacco only as the carrying-trough is in operation to receive and carry it forward.

During the reverse motion of the rack d^5 and cog d^6 , the belts are held at rest by a pawl and ratchet.

The carrying-trough E also acts as a means of measuring the tobacco, the carrying-space within the belts being only large enough to receive the quantity required in a package. The tobacco is compressed as it is received from the hopper, (passing under the roller E^2), which presses down upon it as it passes under it from the hopper into the trough to the consistency desired in a package.

During the process of folding the wrapper, and while the charge of tobacco is being carried forward by the comb F^1 and plunger G, the carrying-trough and feeding-hopper are at rest.

The combs or separators F and F^1 are the means employed for separating and measuring the quantity of tobacco to be placed in the wrapper.

Comb or separator F has simply a rising and falling motion, which is imparted to it by cam D^2 , through the lever d^7 . Its office is to assist comb F^1 in separating the quantity of tobacco required to make the package from that moved forward in and by the carrying-trough.

Comb F^1 has also a falling-motion in the same time as comb F, imparted to it by cam D^3 , through the lever d^8 and its connections. After dropping into po-

sition with comb F, it is, by the action of the same cam and lever, caused to move forward in the trough E—the trough then being at rest—carrying with it the tobacco to a point under and beyond the plunger G. It is then lifted and returns to its first position, and again repeats its forward movement, carrying with it any of the tobacco that may have been left during its first forward movement. This completed, it is returned to its original position.

In lieu of the combs just described, knives of similar shape may be substituted to separate the tobacco, but I prefer the combs for that purpose, it being desirable to detach and separate the tobacco without cutting its fibres.

The plunger G is, by the action of the cam D⁴ and connecting-lever, made to drop into the carrying-trough E, and to take a position behind the quantity of tobacco carried forward by cam I¹. It is then given a forward motion, carrying and forcing the tobacco into a receiving-case, H, which is in position on the same horizontal plane with the carrying-trough to receive it.

This receiving and forming-case H is made the same size (excepting length) as the package to be made. It must be constructed of very thin, yet strong sheet-brass or other suitable metal. This receiving-case is open at both ends, and is held in position to receive the charge of tobacco by means of the connecting-rods h and h¹, fastened to the carrier-holder h².

The receiving-case is also partially open its entire length on the top, (seen plainly in fig. 4.) This is for the purpose of allowing the arm carrying the plunger G (also plunger L) to enter and carry the tobacco to the extreme end of the case; the case being constructed somewhat longer than the package to be made.

When in position to receive the tobacco from the carrying-trough, the receiving and forming-case H is held or rests inside the hollow bed I, (seen more plainly in fig. 5,) which is made open at both ends, and of depth enough so that its top at the sides, when the case H is in position, (as in fig. 4,) is on the same plane as the top of the case H.

At the proper time, and before the charge of tobacco is forced into the case H, a sheet of metal foil or paper, or both, if desired, is drawn by a device that will be hereinafter described, over the top of the bed I and deposited in position for folding.

The case H is then, by action of cam D⁶ and connecting-lever d², dropped down into its position inside the hollow bed I, carrying with and beneath it the wrapper-sheet previously deposited over the bed. This completes the bottom and side folds of the wrapper.

The folding-knives b¹ and b² then in turn complete the top folds, by carrying down on to the top of the case H the sides of the wrapper-sheet left projecting by the action of the forming-case, when dropped into position in the bed I. The knife b³ then makes the upper or first end-fold, the knives b⁴ and b⁵ then turn in the side-folds at the end, the knife b⁶ completing the folding, by turning up the last or lower end-fold.

As soon as the folding-operations described are completed, the plunger G at once forces the charge of tobacco into the case H, and after completing its office, returns to its first position. During the forcing of the tobacco into the case, the folding-knives remain in position as folded over the case, holding it firmly in position in the bed I, until the plunger G is retracted; they are then returned to their first position prior to folding.

These folding-knives are operated, in the proper time, by the action of the cams D⁷, ⁸, ⁹, and ¹⁰ on the main shaft actuating the levers and connecting-levers to which the knives are fastened.

The wrapper of foil or paper being now folded around the receiving and forming-case H, containing the charge of tobacco to be packed, and furnished it from the carrying-trough E by the means described, the left-hand

end of the package being folded and completed, the receiving-case H, with its contents and wrapper, is lifted by the action of cam D¹¹ on the lever d⁹, which lever raises the slide g, to which the carrier-holder h² is firmly attached, (the receiving-case being hung to the carrier-holder by the connecting-rods h and h¹,) to the top of the guide-frames K and K¹, and is carried forward to the groove k², at the left-hand end of the guide-frames, and is dropped down into position, (the slide g following the groove k²;) on the same plane as in its first position.

The plunger L is then, by action of cam D¹¹, through the lever l and slide m, caused to enter the right-hand and open end of the case H. It is then given a forward motion, and forces the tobacco out of the case H, carrying with it the wrapper, folded on the outside of the case.

As the partially-completed package leaves the case H, it enters the box M, provided to receive it. This box is made large enough to receive the package without offering resistance to its entrance. The package is thus forced into the box M, until its unfolded end is in the desired position, prior to being closed by the folding-knives at N.

The operation of these knives is the same as that of knives b³, b⁴, b⁵, and b⁶, as described, for closing the left-hand end of the package.

The box M holds the package firmly during this last folding-operation. The folding being completed, the knives retract to their first position, leaving the completed package to be forced out of the box by the entrance of the succeeding package.

As soon as the partially-made package is delivered from the case H into the box M, the case is carried back to its first position in the bed I, by the same cam, levers, and guides as described in its forward movements. A sheet of paper or foil having been deposited on the bed I, prior to the return of the case, the upper sheet is then folded, and the tobacco again introduced, as previously described.

As the packages completed in the box M are forced from it by the entrance of the succeeding packages, they may be dropped into any proper receptacle provided.

The sheets of paper or metal foil provided for the wrappers of the packages, are deposited, in any desired number, upon the rising and falling carrying-bed O, which is held in position by the standards and guides n n¹ n² n³. This carrying-bed is raised and lowered, at the proper time, by the action of the cam P on the lever P', which causes the bed to rise, pressing (at the close of its upward movement) the uppermost sheet of paper or foil firmly against the lips or flanges o o o o, which project from the top of the standards over the carrying-bed. The lower surfaces of these lips or flanges are provided with a proper adhesive substance, which may be supplied in any suitable manner. These adhesive surfaces, as the wrappers are forced up against them, retain the uppermost sheet, the carrying-bed immediately dropping down to its first position.

A spiral spring, S, is provided on the under side of the carrying-bed, between the bed and lever, for the purpose of taking up the space lost by the successive feeding of the sheets for wrappers.

The paper or foil wrapper being now held by the lips o o o o, the jaws R are made to advance, by the action of cam P on the levers T and T'. These jaws, prior to reaching the wrapper, are made to open, by the action of the stud r on the arm t. The jaws being open, the forward motion is continued, until the edge of the wrapper is between them. They are then closed by a spring, on being released from the stud r, and grasp the wrapper firmly. They are then made to retract, carrying the wrapper to the desired position over the bed I, where it is released from the jaws by a similar method to that described for grasping it.

The wrapper-sheet being now deposited in position, the folding-operations are performed, as hereinbefore described.

A modification of the wrapper-feeding device is shown in fig. 7, but I prefer the operation previously described.

In case the endless belts forming the carrying-trough should become loose, by the stretching of the leather, or from other causes, they can be readily tightened by means of the set-screw V, fig. 2, and after tightening, are held in place by the nuts W, which slide in a groove in the movable bed, to which the shafts on which the pulleys at the right-hand end of the carrying-trough are pivoted. These nuts serve to fasten the movable bed firmly to the bed of the machine.

The levers actuated by the various cams on the main shaft are all held to the face of the cams by a series of spiral springs, fastened to suitable standards on the bed of the machine.

It is obvious that by the improved machine hereinbefore described, a large quantity of packages can be rapidly produced, no manual labor being required, other than the attention necessary to keep the hopper supplied with tobacco, and the wrapper-feeding device with paper or foil-sheets.

The principle on which this machine is constructed can, by modifications, be adapted to the packing of other materials and substances, such as are now packed in small paper wrappers, and it is my intention to so apply my invention.

Claims.

I do not claim, as my invention, the packing of fine-cut tobacco into metal-foil or paper wrappers by machinery; but

I do claim as new, and as my invention—

1. Automatically packing fine-cut tobacco, or other material, into paper or metal-foil wrappers, or both, by machinery, when the various operations of feeding, measuring, and wrapping, necessary to complete the

package, are performed in union with each other, substantially as hereinbefore shown and described.

2. The hopper C and the drum *a*, with the feeding-combs or fingers *b*, having a reciprocating or eccentric motion imparted to them as the drum revolves, all arranged and operating as hereinbefore shown and described.

3. The carrying-trough E, composed of the endless belts *e*, *e*², and *e*³, in combination with the hopper C, the separating and measuring-combs F and F¹, and the receiving and forming-ease H, all arranged and operating substantially as and for the purposes hereinbefore shown and described.

4. The separating and measuring-combs or fingers F and F¹, arranged and operating substantially as and for the purposes hereinbefore shown and described.

5. The plungers G or L, in combination with the carrying-trough E, the receiving and forming-ease H, and the ease M, arranged and operating substantially as and for the purposes hereinbefore shown and described.

6. The receiving and forming-ease H, constructed and operated as and for the purposes hereinbefore shown and described.

7. The employment, in machines for making packages of fine-cut tobacco or other material, of the bed I, as constructed and arranged for receiving the metal foil or paper sheets for wrappers, and operating as an assistant folding-device, in combination with the ease H, and the folding-knives *b*¹, *b*², *b*³, *b*⁴, *b*⁵, and *b*⁶, substantially as hereinbefore shown and described.

8. The folding-knives *b*¹, *b*², *b*³, *b*⁴, *b*⁵, and *b*⁶, arranged and operating substantially as and for the purposes hereinbefore shown and described.

9. The box or holder M, arranged for the purposes hereinbefore shown and described.
